UNITED STATES PATENT OFFICE.

JOSEPH ANDREW GYGAR, OF BRISBANE, QUEENSLAND, AUSTRALIA.

MECHANICAL MOTOR.

1,243,163.

Specification of Letters Patent. Patented Oct. 16, 1917.

Application filed September 14, 1915. Serial No. 50,562.

To all whom it may concern:

Be it known that I, JOSEPH ANDREW GYGAR, a subject of the King of the United Kingdom of Great Britain and Ireland, residing at Brisbane, in the State of Queensland, Commonwealth of Australia, have invented certain new and useful Improvements in Mechanical Motors; and do hereby declare the following to be a full, clear, and 10 exact description of the invention, such as will enable others skilled in the art to which it appertains to make and use the same.

This invention relates to improvements in mechanical motors applicable to be driven 15 by gas, steam or compressed air.

The objects of the invention are to obtain instantaneous expansion and to maintain the full energy of the force employed at the maximum leverage during the complete 20 travel of the piston.

The invention consists of a revolving cylinder or drum mounted upon a shaft: the cylinder or drum is provided with a circular pathway in which is fitted an anvil abutment containing necessary valves for the admission and exhaust of the steam, gas or compressed air used for the motive power.

A semi-circular piston, or a piston connected by a curved arm to a crosshead travels 30 in and around the circular path from one side of the anvil abutment to the other: the circular path is constructed concentrically with the shaft.

A slotted lever fulcrumed upon a vibrating 35 lever suitably supported, is pivotally connected to the rotary cylinder and to the crosshead; this lever controls the travel of the piston and imparts motion to the cylinder.

On the main shaft is a cam, crank, or eccentric engaging with the top of a vibrating lever rocking in a suitable bearing on 40 the base plate of the motor.

To fully describe the invention, reference 45 is now made to the drawings in which:—

Figure 1, is a transverse front elevation of the motor.

Fig. 2, transverse view of cylinder or drum with cover removed.

Fig. 3, transverse back elevation of cylinder or drum.

Fig. 4, longitudinal side elevation of motor partly in section.

The reference numerals indicate like parts 55 in all figures.

(1) is a cylinder or drum constructed with one solid end and provided with a cylinder cover (6) at its open end, in which is a slot (7). This cylinder is keyed to a shaft (2) revolving in pedestal bearing (3). 60

(12) is a vibrating lever keyed upon a spindle (13) rocking in fulcrum bearing (14), pivotally connected to the top end of this lever by a center pin (17) is a vibrating lever (16) solid in the center and slotted at 65 each end, it is connected to the cylinder cover (6) by a pin (18) secured thereto and to the crosshead (11) by a pin (19) secured thereto; the pin (17) does not move in the lever (16) but the latter rotates upon the pin. 70 The extent of the angular movement of vibrating lever (12) is limited, as the center line of same never passes center line of shaft (2).

(9) is the piston and (10) a connecting 75 arm to a crosshead (11), both the piston and the crosshead traveling in and around the circular path of the cylinder.

(8) is an anvil abutment fixed in the circular path in which are fitted necessary 80 valves for controlling the propelling force, but which are not shown in the drawings being outside of the scope of the present invention.

(4) is a crank, cam or eccentric integral 85 with the shaft (2) or fastened thereto by any method permitting the adjustment of angle of "throw" thereof, which engages with the top of a vibrating lever (15) keyed to the spindle (13) of the fulcrum bearing (14). 90

(5) is a space of suitable dimensions for fastening to the shaft (2), necessary mechanism for operating the valves of the cylinder. 95

All four figures of the drawings show the relative positions of the various parts at the moment of the impelling force entering the motor.

In working the invention the impelling 100 force is admitted through valves in the anvil abutment, into the space between the latter and the piston; the piston immediately moves forward, and the slotted arm starts to dip downward, due to the pin (19) fixed 105 to the crosshead (11), and as the impelling force expands and thus loses power, the increased leverage gained by the pin (19) moving outward to the end of lever (16), not only compensates for any loss of power 110

but also allows the piston to rapidly get away, in addition to gaining further leverage due to pin (18) also moving inward.

Both the cylinder and piston rotate at the same time but at varying peripheral speeds in the following manner:—At the moment of impulse the relative distance of the pins (18) and (19) to the center pin (17) is approximately equal, corresponding to the dead center of an engine; when the dead center is passed, the propelling power in expanding, forces the piston (9) connected to the crosshead (11) by the rod (10) around the annular path of the cylinder at a constant accelerating speed in advance of the cylinder, which follows, rotating at a lesser rate of speed.

As the arm (16) rotates upon the pin (17), the distance of the pin (19) from the center pin increases until the pin (19) has reached the extreme limit of the slot in arm (16); the pin (18) at the same time moves inward toward the center pin, when the positions are reversed and the pin (19) starts to travel inward toward the center pin, and the pin (18) outward; this differential dual motion occurs in one complete revolution of the arm (16) around the pin (17). The impelling force acts between the adjacent ends of the abutment (8) and piston (9) when they are in the position shown in Fig. 2. The adjacent faces of these two elements are of substantially the same area. The impelling force causes the piston (9) to move rapidly in the circular pathway of the cylinder away from the front end of the abutment (8), which causes the cross-head (11) to move quickly toward the rear or right hand end of the abutment (8). As the piston (11) thus moves, the pin (19) moves downwardly in the slot (7) of the cylinder and outwardly in the slot (16') of the vibrating lever (16), the latter rotating on its pivot (17). As the vibrating lever (16) dips or rotates on its pivot (17) the connection (18) between the cylinder and said lever (16) causes the cylinder to rotate a relatively slight distance, with the result that when the cross-head (11) has traveled to a position adjacent the right hand or rear end of abutment 8, the cylinder has been caused to rotate a small degree by virtue of the connection (18) between the cylinder and the slot (16') in the vibrating lever (16). This rotative movement of the vibrating lever (16) causes the pin (19) of the cross-head (11) to move in a downward direction and outwardly in the slot (16') of the lever (16), as stated, and causing the connection (18) between the cylinder and the lever (16) to move in an upward arc and inwardly in the slot (16') of the lever (16), increasing the leverage of the lever (16) to facilitate the rotative movement of the cylinder and also facilitate movement of

the cross-head (11) toward the abutment (8). As the impelling force expands and loses power this increased leverage gained by pin (19) moving outwardly to the end of the lever (16), not only compensates for any loss of power but also permits the piston (9) to get away quickly from the abutment (8), the inward movement of the pin (18), with relation to the lever (16) giving further leverage to said lever.

As the cylinder thus rotates, it being fixed to the shaft (2), the latter and the crank or eccentric (4), connected to the shaft, are rotated with the shaft. As said crank or eccentric (4) is rotated in the manner just stated, and being disposed in the slot (15') of the vibrating lever (15), the spindle (13) to which said lever (15) is fixed, is caused to rock. The lever (12) fixedly connected to the spindle (13) is also caused to rock or vibrate between its position shown in Fig. 1 and the center line of the shaft (2). The said vibration of the lever (12) causes vibration of the lever (16), producing the aforesaid increased leverage and thereby assisting and facilitating the forward movement of the piston (9).

It being understood that the charge of the impelling force takes place between the piston (9) and the abutment (8), and that the cylinder rotates at less speed than the piston during the impulse stroke, it is explained that the piston then lags at the end of the impulse stroke until the abutment (8) again overtakes the piston, as at the commencement. This lagging stroke of the piston is the exhaust stroke.

Although it might appear that the rotary motion would be arrested by the action of the impelling force against the piston (9) and the re-action of same on anvil (8), this is not so, practice having proved that both the piston and cylinder revolve at varying peripheral rates of speed.

What I declare as my invention, and desire to secure by Letters Patent is:—

1. A rotary engine including in combination, a shaft, a cylinder keyed to the shaft and having a circular pathway formed therein concentric with said shaft, an abutment fixed in said pathway, a piston and cross-head connected together adapted to travel in said pathway, a vibrating lever mounted adjacent the cylinder, a slotted vibrating lever pivotally connected to the upper end of the aforesaid lever, a connection between the piston and said slotted vibrating lever which is slidable in said lever, a connection between the cylinder and said slotted vibrating lever and which is slidable in the slot of said slotted lever, and means between the shaft of the cylinder and the first mentioned vibrating lever to vibrate the latter and consequently shift said slotted vibrating lever during rotation of the drum.

2. A rotary engine including in combination a shaft, a cylinder keyed to the shaft and provided with an annular pathway therein concentric with said shaft, an abutment fixed in the pathway, a piston and a cross-head connected together and adapted to travel in said pathway, a vibrating lever mounted to vibrate adjacent the cylinder, a slotted lever pivoted on said vibrating lever, a pin secured to the cylinder and having slidable engagement with said slotted lever, a connection between said slotted lever and cross-head, and means for vibrating the vibrating lever.
- 15 3. A rotary engine including in combination a shaft, a cylinder keyed to the shaft and provided with an annular pathway concentric with said shaft, an abutment fixed in the pathway, a piston and a cross-head connected together and adapted to travel in said pathway, a vibrating lever mounted adjacent the cylinder, means to operate said vibrating lever from the shaft, a slotted lever pivoted upon said vibrating lever, a pin secured to the cylinder and adapted to engage said slotted lever.
- 25 4. A rotary engine including in combination a shaft, a cylinder keyed to the shaft to rotate therewith and having an annular pathway concentric with the shaft, driving factors mounted in the pathway, one of which is fixed therein, a vibrating lever mounted adjacent the cylinder, means to operate said lever from the shaft, and a slotted lever pivotally mounted on the aforesaid vibrating lever and having connection with the cylinder and with one of said driving factors.

5. A rotary engine including in combination, a cylinder keyed to the shaft to rotate therewith and having an annular pathway therein concentric with the shaft, driving factors mounted in the pathway, one of which is fixed therein, a vibrating lever mounted adjacent the cylinder, means to operate said lever from the shaft, and a slotted lever pivotally mounted on the aforesaid vibrating lever and having connection with the cylinder and with one of said driving factors.

10 15 20 25 30 35 40 45 50 55

In testimony whereof, I affix my signature, in presence of two witnesses.

JOSEPH ANDREW GYGAR.
